DESCRIPTION

U.S. PATENT DOCUMENTS

D392,269 S	3/1998	Mason
D402,645 S	* 12/1998	Garguilo .....
D422,985 S	* 4/2000	Bright .....
D442,971 S	* 5/2001	Ginocchio .....
D471,226 S	* 3/2003	Gray .....
6,585,591 B1	7/2003	Baerlocher

The sole FIGURE depicts a front view of a display screen or portion thereof with a graphical user interface, showing our new design.

The forward slanted diagonal lines illustrate a contrast in appearance.

The outermost broken lines in the FIGURE illustrate a display screen or portion thereof. The remaining broken lines illustrate portions of the graphical user interface that do not form part of the claimed design.
